UNITED STATES PATENT OFFICE.

FRANK L. WRIGHT, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,980, dated December 7, 1897.

Application filed October 4, 1897. Serial No. 654,090. Term of patent 14 years.

To all whom it may concern:

Be it known that I, FRANK L. WRIGHT, a citizen of the United States, residing at Chicago, in the county of Cook and State of Illinois, have invented a new and original Design for Prism-Lights, of which the following is a specification.

My invention relates to designs for prism-lights.

Figure 1 is a plan view. Fig. 2 is a cross-section on line 2-2.

AA are a number of concentrically-arranged figures on one side of the prism-light. There are prisms BB on the other side.

The essential features of my design are 15 found in a prism-light comprising a body with prisms on one side and concentrically-arranged non-interlacing ornamental figures on the other side.

I claim—

20 A design for a prism-light, substantially as shown and described.

FRANK L. WRIGHT.
